Sterling P. Buck,

Attorney.

UNITED STATES PATENT OFFICE.

DAVID R. BONE, SR., OF OGLESBY, TEXAS.

PROCESS OF PRODUCING AND SEASONING HYDRATED LIME.

Application filed September 21, 1923. Serial No. 664,069.

To all whom it may concern:

Be it known that I, DAVID R. BONE, Sr., a citizen of the United States, residing at Oglesby, in the county of Coryell and 5 State of Texas, have invented certain new and useful Improvements in Processes of Producing and Seasoning Hydrated Lime, of which the following is a specification.

This invention relates to an improved 10 process of producing and seasoning hydrated lime.

One object of the invention is to provide a process of making an exceedingly pure and high quality of hydrated lime for the 15 various purposes for which hydrated lime is required or used.

Other objects and important features will be pointed out or implied in the following details of description and in the claims.

20 In carrying out the foregoing objects, I preferably (though not necessarily) employ the form of lime-kiln shown in my Patent No. 1281902, patented October 15th, 1918, and to employ the dipping or wetting device 25 shown in my Patent No. 1469209.

In the accompanying drawings, forming part of this specification, Fig. 1 is a somewhat diagrammatic and perspective view showing one form of apparatus or combination of devices which may be employed in carrying out the process. Fig. 2 is a sectional detail view, the section being taken in a plane passing vertically and longitudinally and approximately through the 35 center of the concrete storage and seasoning bin. Fig. 3 is a view showing, in top plan and lateral section, a form of grate or screen bottom for use in the cars which carry the burned lime, immerse it in the dipping vat 40 or tank, then hold it in compressed bulk while it is being disintegrated, or while its hydration is being completed after being dipped or wetted.

To reiterate briefly the construction and 45 operation of the lime-kiln of my Patents Nos. 1281902 and 1469209. The lime-kiln includes the chamber 1 which receives the lime and is provided with doors or inlets 2 and a chimney 3. The doors 2 communicate with furnaces 4, on opposite sides of the kiln-chamber 1, and each furnace 4 is provided with a grate 5, a door 6 and one or more rotary stokers 7. Under each grate 5 is a chute 8 whose upper end is a hopper 9 that receives the ashes and cinders that fall through the grate. The bottoms of

the chutes terminate in boxes 10 which have doors 11 through which the ashes can be removed. These boxes have grate bars 12 on which fuel can be placed through doors 60 13. The heat from the boxes 10 passes up the chutes 8 and assists in effecting complete combustion in the furnaces 4, so as to eliminate black smoke (or greatly reduce the carbon) from the products of combustion 65 that pass through the doors 2 into the kiln-chamber. Gates 24 may be closed to cut off communication between the furnaces 4 and boxes 10, and gates 25 may be closed to cut off communication between the furnaces 70 4 and the kiln-chamber.

The bottom of the kiln-chamber is in the form of a funnel or hopper 26 and has a gate 26^a which can be opened to let the hot newly kilned lime lumps or unslaked 75 and undivided burnt limestone into cars 27 which have screen or grate bottoms, one form of which is shown in Fig. 3. The cars travel on railway tracks 30, 31, 32 and 33 which are connected by switches the same 80 as in my Patent No. 1,469,209 except that I here add the switch that connects the track 33 to the track 30. This track 30 included a movable section which forms part of a lift or car-lowering and raising 85 device 30^a which has under it a vat or water-tank 30^b.

All the foregoing, except the cars' screen bottoms and the track 33 (including its switch) relates to matter shown in my previous patents above mentioned; and, referring now to Fig. 3, it will be seen that a strong and practical bottom of this kind may be formed of flat bars of iron disposed vertically edgewise. The cross bars 28 may be notched so as to provide spacers between the notches, and the longitudinal bars 29 may be seated in these notches and secured by electric welding or other appropriate means; or, a screen bottom of this kind may be cast integrally and then annealed. The advantages of a screen bottom are to permit water (from the water-tank 30^b) to rise into contact with the lower part of the bulk of lime, in the car, while the upper part of the bulk is being wetted by the water that flows over the top of the car, thus very quickly wetting all of the lumps of lime in the bulk, not only saving time of the operator, but also starting the hydration substantially simultaneously for all of the lumps of the bulk, thus assuring the maxi- 100 105 110

2
 mum evenness of hydration; and when the bulk of lime in the car has been immersed in the water (of the water-tank) long enough to properly start the hydration, and 5 long enough for the lime to absorb enough water to complete its hydration, the car is raised, the surplus water drains through the screen bottom, back into the water-tank, and the car then carries its bulk of lime onto 10 the track or siding 31 where it remains until the hydration is complete. Any appropriate water-gage may be employed in the water-tank for measuring the water before and after each car-load of lime is dipped or immersed, thus gaging the quantity of water taken up by each load or bulk of lime. In 15 practice, the cars are filled only about one-third full of the lime-lumps, and when the hydration is complete the cars are substantially 20 full, owing to the expansion of the bulk in hydrating. The sides and ends of the cars are imperforate, so that the atmosphere is excluded to a very considerable extent, and the gages are preserved in the bulk 25 of lime, especially in view of the lime becoming more and more compact as it tends to expand and is restricted by the sides and ends of the cars. The lime is thus kept in bulk in the cars on the siding 31 about 30 twenty-four hours which is usually the time required for the hydration to be completed, enough cars being provided, and a sufficiently long siding 31, for continuing the process without having to wait for the completion 35 of the hydration in any one of the cars. The tracks 31 and 32 are connected by a switch (shown in my Patent 1,469,209, but not shown here), and the cars of hydrated lime can be switched first to the 40 track 32 and then to the track 30 where it joins the track 33.

The track 33 terminates in a combined car-lift and tipple of any appropriate kind which is shown at 34. It is provided with 45 a separating screen 35 from which the lumps or cores may fall into a conveyer trough 36 and be carried away by a screw conveyer 37. The hydrated lime-powder falls into a storage and seasoning bin 38 50 of large capacity, preferably holding about 100 tons. This bin may be of any preferred shape, construction and material, but is here shown relatively long and narrow so that its contents can be shifted by a single 55 screw-conveyer 39 such as shown in Fig. 2. This conveyer is at the bottom of the bin, so that the lime first deposited therein is the first to be shifted by the screw-conveyer to the farther end of the bin from the tipple 60 at the bin's receiving end. Therefore, the best seasoned or cured lime is removed first (by means presently described) while the later receipts of lime in the bin have time to cure or season before being removed. 65 In the discharge end of the bin 38 is an

endless chain-and-bucket elevator, its shaft 40 being hollow and having an inlet 41 and an outlet end 42. The buckets of its endless belt or chain are shown at 43 (Fig. 2). Its endless belt or chain is operated by a shaft 44, sprocket 45, chain 46, second sprocket 47 (Fig. 2), second shaft 48, bevel gear wheel 49, second bevel gear wheel 50, main driving shaft 51, and main driving wheel 52 which may be operated by an engine, motor or other source of power. This driving shaft may be geared with the stokers 7 in any appropriate way or by any appropriate means so as to operate the stokers. 75 It is also operatively connected to a fan 53 through the medium of a belt 54 which runs on the fan's pulley and on a pulley 55 of the main shaft. The fan communicates with the outlet 42 through a tubular connection 56, and its outlet end communicates with a centrifugal separator 57 through a tubular connection 58.

The fan separates the lime into its indivisible grains or particles and mixes them with the air which passes therewith into the centrifugal separator in which the centrifugal force carries the heavier particles against the wall of the separator, out of the main air current, so that they (the heavier particles) pass by gravity through an outlet tube 59 into a receiving chamber 60. The finer particles pass with the air through a tubular connection 61 into a second centrifugal separator in which the greater part of the lime is separated from the air and passes down through an outlet 63 into a receiving chamber 64. The air and a residual extremely fine lime powder passes thence through a tubular connection 65 into a cloth receiver or air-separator or dust collector 66. This may be composed of any appropriate cloth stretched on a cubical open-sided frame, so that the air can escape through the meshes of the cloth, but the dust remains on the inner surface of the cloth and will collect in volume, and finally its weight will cause it to fall. It is caught in a receiving chamber 67 from which it may be withdrawn to supply a demand for such exceedingly fine lime-powder. If the accumulation of lime on the inner surface of the dust collector gets rather thick before falling, it retards the escape of air and lessens the efficiency of the apparatus; so I may provide any appropriate means for shaking the cloth so as to accelerate the falling of the accumulation of lime dust. One means, as here shown, may consist of an arm 68 secured to the dust collector, and an arm 69 secured to the shaft 51. As the shaft 51 rotates, its arm repeatedly strikes the arm 68, and the latter causes the cloth to yield so as to let the arm 69 pass the arm 68 after striking the latter.

130 A bagging machine of any appropriate

kind (not shown) may be used instead of or in connection with the receiving chambers 60, 64 and 67 or any one of them; or the different grades of lime may be removed from these receptacles by any appropriate means.

Referring now to Fig. 2, it will be seen that the conveyer 39 may be driven by the main shaft 51, through the medium of the 10 gear wheels 49 and 50, the shaft 48, a pair of bevel gears 70, a shaft 71, and a pair of bevel gears 72.

While I have shown and described a combination of devices cooperating in a particular way, viz., through the main shaft 51, the railway tracks and other conveying means, it is not intended to limit this invention to these specific operating and conveying means, nor to the specific forms of devices here shown; for the process may be carried into effect by other means or other arrangements of devices; for instance, I may either (as a modification) dispense with the elevator 34 and incline the track 25 so as to dump the hydrated lime into the screening separator 35; or I may entirely eliminate the elements 34, 35, 36 and 37, and dump the lime (cores and all) into the bin 38; in which case, I could provide a screening separator between the outlet 42 and the inlet 56 of the fan 53. In this or any other form of operating mechanism, it is within the scope of the invention to provide clutches and speed-controlling devices 30 wherever applicable and advantageous. Any appropriate changes may be made within the scope of the inventive ideas, as implied and claimed.

Some of the advantages of these improvements are as follows: (First)—The process begins in the improved combination of kiln and furnaces shown and claimed in my above mentioned patents, so that the lime is free from dis- 45 coloration of smoke and other impurities, and in which over-burning and under-burning are avoided. (Second)—By taking the lime direct from the kiln while most of the kilning heat is in the unbroken 50 stones or lime-lumps and immediately immersing these hot unbroken lumps in water, this makes it impossible for the air to have any detrimental effect on the lime. (Third)—The cars each having open top, 55 screen bottom and imperforate sides and ends or walls, this permits wetting of the hot lumps of lime by water flowing both upward and downward in the cars, so all parts of the bulk of lime (in the respective cars) 60 are thoroughly and quickly wetted and permitted to absorb sufficient water to complete the hydration after the surplus water is drained out through the screen bottom and remains in the water-tank. By thus 65 draining off the surplus water, I avoid such

over-wetting that would result in producing an over-wet hydrated lime which is difficult to handle and which would have to be dried by evaporation and thus lose a valuable quantity of a certain chemical element of the lime. By having only the unbroken or original size lumps of lime in each car, this provides ample spaces and passages between the lumps for permitting quick access of the water to all surfaces of the lime lumps, so that an absorption of the water is not difficult or retarded, in contradistinction to the processes wherein the lime lumps are crushed into small pellets. By measuring the depth of water in the dipping vat or water-tank immediately after immersing a car and its content of lime, then raising the car when the depth has decreased to a predetermined proper extent, this allows the proper amount of water (and no more) to be absorbed by the lime. (Fourth)—By providing the siding 31 and the sufficient number of cars to remain on this siding with their contents of lime in which the hydration is completed after wetting of the lime, this not only saves time, by permitting the burning, wetting and other steps to continually proceed; but also produces the best quality of hydrated lime, by the imperforate walls of the cars and the compressed bulks of lime excluding air from the interior of the bulks, also retaining the gases within the bulks. (Fifth)—After hydration is completed, all the unburned cores, being uncrushed, are easily and entirely separated from the burned lime, in contradistinction to the processes in which the burned lime and cores are crushed and intermixed.

(Sixth)—Through the screening and separating processes here described, three different grades of fine, finer and finest lime powder are obtained in separate receivers, and besides, a mixture of all three grades can be taken from the storage bin to supply a demand for a comparatively cheap lime, as for agricultural purposes. The cores can be burned over with the raw lime stone.

The bin 38 may be provided with a cover 115 of any appropriate kind (not shown) for protecting the lime from atmospheric draughts during its seasoning period.

This process can be carried out with a small amount of labor, because all the devices are or may be power-operated.

This process, in its broadest form, is in successful operation, by the applicant, in the Lone Star Lime Works, at Oglesby, Texas.

What I claim as my invention is:—

1. The process of hydrating lime, comprising placing lump-lime in a screen-bottom car, dipping the car in water, and draining the excess water from the lump-lime through the screen-bottom of the car.

2. The process of hydrating lime, comprising placing lump-lime in a screen-bottom car while the lime is hot from the kiln, dipping the car and its content of hot lump lime in water, and raising the car and its content of lump-lime from the water and permitting the excess of water to drain through the screen-bottom of the car.

3. The process of hydrating lime, comprising placing lump-lime in a screen-bottom car, dipping the car and its content of lump-lime in water, raising the car and its content of lump-lime from the water and permitting the excess water to drain from the lump-lime through the screen-bottom of the car, and placing the lime in a curing bin

after the lump-lime has disintegrated in the screen-bottom car.

4. The process of hydrating lime, comprising placing hot lump-lime in a screen-bottom car, dipping the car and its content of lump-lime into a body of water, removing the car from the body of water and permitting the excess water to drain from the lump-lime, keeping the content of lime confined in the car until the lump-lime has disintegrated in consequence of the water absorbed thereby, and placing the disintegrated lime in a curing bin.

In testimony whereof I affix my signature.

DAVID R. BONE, Sr.
